UNITED STATES PATENT OFFICE.

WILLIAM E. MOORE, OF PORTLAND, OREGON.

HEATING-FURNACE.

SPECIFICATION forming part of Letters Patent No. 248,493, dated October 18, 1881.

Application filed February 10, 1881. (Model.)

To all whom it may concern:

Be it known that I, WILLIAM H. MOORE, a resident of the city of Portland, in the county of Multnomah, State of Oregon, having invented 5 certain new and useful Improvements in Heating-Furnaces, of which the following is a specification.

My invention relates to that class of heating devices known as "hot-air furnaces;" and it 10 consists in certain particulars of construction and combinations of parts, which will be more fully described in the ensuing specification, and particularly pointed out in the claims at the close thereof.

15 In the annexed drawings, Figure 1 is a front elevation of my improved furnace. Fig. 2 is a plan view of the top of the furnace, showing the pipes. Fig. 3 is a longitudinal vertical section, showing the fire-box and arrangement of 20 check-plates and cold-air passages in back part of furnace; and Fig. 4 is a view in vertical section through the back part of furnace, showing the arrangement of check-plates and cold-air passages.

25 A in Fig. 1 represents the body of furnace, it being of the shape shown, wider at bottom than top.

S represents the fire-box, and k represents the cold-air entrance in front of furnace.

30 d d d d d are apertures in the sides of the fire-box S, and the cold air coming in through front entrance, k, and between side of furnace and through the apertures d d d d d prevents excessive heat, and preserves the parts of furnace otherwise likely to burn out from doing so.

35 B B represent pipes on top of the furnace, and extending the entire length of furnace, and beyond, on each end and outside of brick-work, they are connected with each other by 40 pipes C C, one on each side. They, in turn, are connected in front with central pipe, D, which conducts the smoke, &c., from the furnace into the chimney.

45 E is the throat or smoke-exit when direct draft is in operation. Its upper end fits into pipe D, and its lower end into body of furnace A. Placed in throat E is damper e, revolving therein, as shown in Fig. 3, one end being pivoted in throat E, and the rod r extending along 50 the furnace-body directly under central pipe, D, out beyond the front of the furnace, a handle, f, being formed on that end, by which it can be

operated from the front of the furnace. A suitable bearing on top of front of furnace retains it in position.

55 G G are pipes which connect with pipes B B, and these pipes G G connect and fit into pipes H H, which lead from and fit into the back part of furnace-body, as shown in Fig. 3.

60 Draft-checks I I are adjustable caps fitted in the front ends of each pipe B. They are in skeleton form—that is, the part fitting inside of pipes B. They have a cap provided with a handle, h, and can be adjusted close up to the pipe or pulled out, as desired, to check the 65 draft. They also accomplish the object of taking up into the furnace foul air or other obnoxious atmosphere usually found in cellars and basements.

70 In the back portion of the furnace, running the same at right and left angles crosswise of each other, are cold-air passages J J, as shown in Figs. 3 and 4, and fitted in the same portion of furnace-body are checks or plates K K, the back part of the fire-box S also forming and 75 operating as a check-plate. These checks K K K are for the purpose of checking the draft and creating a more intense heat in back portion of furnace-body.

80 l l in Figs. 2 and 3 are adjustable caps fitted into flues H H, and are for the purpose of allowing the accumulations of soot, &c., to be cleaned out from the flues when desired. In connection with the draft-checks I I the whole arrangement of pipes can be cleaned out at will. 85

85 The operation of my furnace is as follows: When the damper e is turned off the heat and smoke, instead of going out at throat E, goes down and out at pipes H H into the pipes G G, thence into B B, thence into pipes C C, through 90 pipe D, and into chimney. During this operation these pipes on top of the furnace become powerful radiators of heat, and more warmth from the furnace is consequently obtained. The check-plates K K K restrain the draft and hold 95 the hot air until the entire back part of furnace becomes heated. The cold-air passages J J also produce more heat in the building by the cold air passing through against their heated surfaces, thereby becoming hot air.

100 The draft-checks I I are a very important feature in my invention, as by means of them the draft of the furnace can be regulated by adjusting them from or into the pipes B B, and

they perform the important sanitary function of taking into the furnace foul or obnoxious air from the cellar or basement in which the furnace may be, and when it is necessary to clean out the pipes they can be taken out and the pipes cleaned.

Having described my invention, what I claim as new, and desire to secure by Letters Patent, is—

10 1. In an air-heating furnace, the combination, substantially as before set forth, of the furnace-body, the open air-pipes running diagonally across the furnace-body and crossing each other at the center thereof, and the check-plates for forming a tortuous passage from the fire-box to the smoke-exit.

15 2. In an air-heating furnace, the combination, substantially as before set forth, of the smoke-exit provided with a damper, the hori-

zontal pipes H, leading one from each side of the back plate of the furnace-body, the vertical pipes G, leading therefrom and connected at the top with the longitudinal pipes B, the skeleton draft-checks, the pipe D, and the connections C C.

20 3. In combination, the whole arrangement of furnace-body A, fire-box S, with back of same forming check-plate K, apertures d d d d d, front entrance for cold air, k, check-plates K K, cold-air passages J J, pipes H H, adjustable caps l l, pipes G G, pipes B B C C, draft-checks I I, central pipe, D, smoke-exit E, damper e, and handle r f, substantially as arranged and described, and for the purposes set forth.

25 W. H. MOORE.
